UNITED STATES PATENT OFFICE.

ROLLA MOUNT, OF KANSAS CITY, MISSOURI, ASSIGNOR OF TWO-THIRDS TO
WILLIAM D. BROOKS, OF KANSAS CITY, MISSOURI, AND ARTHUR H.
GILLESPIE, OF PITTSBURG, PENNSYLVANIA.

AWNIN.

SPECIFICATION forming part of Letters Patent No. 746,732, dated December 15, 1903.

Application filed December 29, 1902. Serial No. 136,906. (No model.)

To all whom it may concern:

Be it known that I, ROLLA MOUNT, a citizen of the United States, residing at Kansas City, in the county of Jackson and State of Missouri, have invented new and useful Improvements in Awnings, of which the following is a specification.

My invention relates to awnings for storefronts; and the object of my invention is to provide an awning which will dispense with the usual oblique bracing-bars employed for supporting the style of awnings in present general use.

In carrying my invention into effect I construct the awning-frame of a plurality of rods or pipes which pass into the interior of the building through suitably-located openings. Said rods or pipes are supported and guided by pairs of antifriction-rollers, whereby the rods are longitudinally slideable in and out of the front of the building. When the rods are in, the bulk of the awning is rolled around a roller of the usual form, which is mounted on the front of the building, and when the rods are extended outwardly they carry with them the awning, which then lies in an approximately horizontal plane, as indicated in Figure 1 of the accompanying drawings.

Referring now to said drawings, Fig. 1 is a sectional side elevation of the preferred form of my invention, the awning being shown as rolled up and the extended position of the awning and its frame being indicated by dotted lines. Fig. 2 is a front elevation of the awning in closed position, the cords and weights within the building being shown in dotted lines. Fig. 3 is a plan view of the awning-frame and certain other parts referred to hereinafter, the antifriction-rollers and the awning itself being omitted for clearness. Fig. 4 is an enlarged sectional plan view of one of the housings containing two pairs of rollers. Fig. 5 is a further enlarged detail view of the front end of one of said housings. Fig. 6 is an enlarged sectional view of the rear end of said housing, taken on a line corresponding to line *a b* of Fig. 1.

Referring to Figs. 1 and 2, 1 designates the plate-glass front of a shop-window, 3 the sash-bar at the top of said glass, and 4 the trans-

som or prism glass above the sash-bar. 5 is the ceiling of the room, and 6 and 7 are respectively the wooden top and the back of the "window." Supposing, for example, that the awning is twelve feet or less in length, it will be supported by two rods or pipes 8, which are preferably passed through holes bored through the sash-bar 3. For awnings twenty-four feet in length three of the rods or pipes 8 will be provided. Each of these rods 8 is supported and guided by two pairs of antifriction-rollers 9 and 10, the arrangement of which is shown in Figs. 1, 4, 5, and 6. Each two pairs of said rollers are mounted in a housing 12 13, which comprises two side plates 12, connected near their ends by integral bridges 13. The front ends of the side plates 12 have lateral ears 14, which are secured by screws to the inner side of the sash-bar 3. The rear ends of said side-plates 12 have lateral horizontal ears 15, which are secured by screws to the top 6 of the window. The pairs of rollers 9 and 10 are arranged vertically, as shown, and between them extends a rod 8. The outer ends of rods 8 are bent upwardly, or, if tubular, elbows 8' are employed, and secured to the ends of said rods, respectively, are iron plates 16, to which is secured a wooden bar 17, to which the awning 18 is secured near its outer edge. The inner edge of the awning is attached to a roller 19, of which 20 is one of the bearing-brackets, and secured on said roller is a sprocket 21, from which hangs a chain 23, which is operated by any suitable or preferred mechanism, none being shown, as my invention does not relate to such. To the inner end of each rod 8 is attached a cord or cable 24, which runs forwardly above the rod and passes up around the upper inner roller 10, in which a special groove 25 is formed to receive said cord. Each cord passes up to and over a pulley 26, secured to the ceiling, and supports a suitable weight, as 27. These weights by acting through the intermediacy of their cords 24 exert outward pressure upon the awning-rod 8, and when the sprocket-chain is permitted to move said weights will extend the awning over the sidewalk, as indicated in Fig. 1. To roll up the awning, 100

the roller 19 is operated by means of the chain 23.

In the drawings the rods 8 are arranged horizontally; but if it be preferred to incline the awning downwardly toward the front the housings 12 13 may be secured at the proper angle to impart the desired slant to the awning, as will be readily understood.

Having now fully described my invention, what I claim as new, and desire to secure by Letters Patent of the United States, is—

1. The combination of a plurality of longitudinally-slidable awning-supporting rods, said rods being supported and guided by antifriction-rollers, a bar connecting the outer ends of said rods, cords attached to the inner ends of said rods, said cords extending forwardly, around said rollers, pulleys suspended from the ceiling, weights suspended from the pulleys, substantially as described; substantially as and for the purpose specified.

2. The combination with a sash-bar 3 and the top of a window, of a plurality of longitudinally-slidable rods, said rods passing through openings in the sash-bar, housings secured to the inner face of the sash-bar and to the top of the window, two pairs of antifriction-

rollers in each housing, said rods passing between said pairs of rollers, cords attached to the inner ends of said rods, said cords extending forwardly around said rollers, pulleys suspended to the ceiling, weights and cords suspended from said pulleys, substantially as described.

3. The combination, with a sash-bar 3 and the top of a display-window, of a plurality of longitudinally-slidable rods, passing through openings in said sash-bar, a bar connecting the outer ends of said rods, an awning attached to said bar, a roller upon which the awning may be wound, said roller being held at about the same height as said bar, housings secured to the top of the display-window and to the inner face of the sash-bar, two pairs of antifriction-rollers in each housing, said rods passing between said pairs of rollers, and two of said rods being provided with cords and weights for extending the awning; substantially as described.

In testimony whereof I affix my signature in the presence of two witnesses.

ROLLA MOUNT.
